US00D896633S

(12) **United States Design Patent** (10) Patent No.: **US D896,633 S**
 Balzer et al. (45) Date of Patent: ** *Sep. 22, 2020

(54) **CONTAINER**(71) Applicant: **GOLDEN STATE FOODS CORP.**,
Irvine, CA (US)(72) Inventors: **Larry Balzer**, Waterford, WI (US);
Linda Balzer, Waterford, WI (US);
Drew Chrisohon, Statham, GA (US);
Dan Wenker, Atlanta, GA (US)(73) Assignee: **GOLDEN STATE FOODS CORP.**,
Irvine, CA (US)

(*) Notice: This patent is subject to a terminal disclaimer.

(**) Term: **15 Years**(21) Appl. No.: **29/678,516**(22) Filed: **Jan. 29, 2019**(51) LOC (12) Cl. .... **09-03**(52) U.S. Cl. **D9/425**

(57) **CLAIM**

The ornamental design for a container, as shown and described.

DESCRIPTION

FIG. 1 is a top perspective view of a container, showing our new design.

FIG. 2 is a bottom perspective view of the container.

FIG. 3 is a top plan view of the container.

FIG. 4 is a bottom plan view of the container.

FIG. 5 is a left side view of the container.

FIG. 6 is a right side view of the container.

FIG. 7 is a front view of the container; and,

FIG. 8 is a rear view of the container.
